(57) **CLAIM**

The ornamental design for a convertible swaddle garment, as shown and described.

DESCRIPTION

FIG. 1 is an exploded front elevation view of a convertible swaddle garment with the wings detached showing our new design;

FIG. 2 is a front left perspective view of the convertible swaddle garment showing our new design in an expanded configuration;

FIG. 3 is a front elevation view of the expanded configuration;

FIG. 4 is a rear elevation view of the expanded configuration;

FIG. 5 is a right side view of the expanded configuration;

FIG. 6 is a left side view of the expanded configuration;

FIG. 7 is a top plan view of the expanded configuration;

FIG. 8 is a bottom plan view of the expanded configuration;

FIG. 9 is a front left perspective view of the convertible swaddle garment showing our new design in a first contracted configuration with closures closed;

FIG. 10 is front elevation view of the first contracted configuration;

FIG. 11 is a rear elevation view of the first contracted configuration;

FIG. 12 is a right side view of the first contracted configuration;

FIG. 13 is a left side view of the first contracted configuration;

FIG. 14 is a top plan of the first contracted configuration;

FIG. 15 is a bottom plan view of the first contracted configuration;

FIG. 16 is a front left perspective view of the convertible swaddle garment showing our new design in a second contracted configuration with the closures opened;

FIG. 17 is a front elevation view of the second contracted configuration;

FIG. 18 is a rear elevation view of the second contracted configuration;

FIG. 19 is a right side view of the second contracted configuration;

FIG. 20 is a left side view of the second contracted configuration;

FIG. 21 is a top plan view of the second contracted configuration; and,

FIG. 22 is a bottom plan view of the second contracted configuration.

The broken lines of even length shown in the drawings illustrate portions of the convertible swaddle garment that

(Continued)

form no part of the claimed design. The broken lines of uneven length define the boundaries of the claimed design.
